UNITED STATES PATENT OFFICE.

EDWARD EDWARDS, OF HAWKINSVILLE, GEORGIA.

IMPROVEMENT IN HARNESS-SADDLES.

Specification forming part of Letters Patent No. **152,090**, dated June 16, 1874; application filed February 14, 1874.

To all whom it may concern:

Be it known that I, EDWARD EDWARDS, of Hawkinsville, in the county of Pulaski and State of Georgia, have invented a new and useful Improvement in Harness-Saddles, of which the following is a specification:

The invention will first be fully described, and then pointed out in the claim.

In the accompanying drawing, Figure 1 is a longitudinal section of my improved saddle, taken on the line *xx* of Fig. 2. Fig. 2 is a top view of the saddle.

Similar letters of reference indicate corresponding parts.

A represents the top of the saddle. B is the padding. C is the adjustable back-strap. D D are the thill-loops, connected with the back-strap by the buckles E E. F F are the terrets. G is the check-rein hook. This check-hook and the terrets are attached to plates H, which are each bent or formed with a recess, which admits the back-strap, and is fastened to the top A of the saddle by means of rivets I through their ends, as seen in the drawings.

This arrangement allows the back-strap to "render" or slide on the top of the saddle, as it is kept securely in position by the loop-plates H and by leatherloops J J on the sides of the saddle. The back-strap is made round

at these points, as indicated at K K; but it may be flat throughout, if desired.

By this construction the bearing of the thills is equalized on the saddle, as either one of the thills can rise or fall, and are self-adjusting independently of each other. Another advantage is, the back-strap is always in plain sight, and is consequently safer than when made in the ordinary manner, besides being more durable and quite as easily constructed.

The hook and back-strap loop may be made in one piece, and the hook and terrets are fastened with common or fancy screws.

Having thus described my invention, I claim as new and desire to secure by Letters Patent—

The combination, on a harness-saddle, of a flat one-piece back-strap, C, having rounded parts K K, with hook and terrets having recessed plates H and the loops J J, by which said strap is held in position, and through which it is allowed to slide, as and for the purpose specified.

EDWARD EDWARDS.
